(57) **CLAIM**

The ornamental design for an interchangeable dismountable hinged box, as shown and described.

DESCRIPTION

FIG. 1 is a top perspective view of an interchangeable dismountable hinged box, showing our new design; FIG. 2 is a bottom perspective view thereof; FIG. 3 is a front elevation view thereof; FIG. 4 is a rear elevation view thereof; FIG. 5 is a right-side elevation view thereof; FIG. 6 is a left-side elevation view thereof; FIG. 7 is a top plan view thereof; and, FIG. 8 is a bottom plan view thereof.

The broken lines in the drawings depict portions of the interchangeable dismountable hinged box that form no part of the claimed design.

1 Claim, 8 Drawing Sheets
